WALTER D. HAINLINE, OF SAN FRANCISCO, CALIFORNIA

PIN-TUMBLER LOCK

Application filed December 13, 1928. Serial No. 325,760.

The invention relates to improvements in locks of the type having a plurality of spring-pressed locking pins or tumblers which are 5 slideable in a stationary lock cylinder and projectible into pin bores in a rotatable plug mounted in a bore of said cylinder, the plug being formed with a longitudinal key-way and being equipped with the releasing pins for the tumblers actuated by insertion of a 10 key into said key-way. Locks of this type are often quite easily picked by operation of a suitable instrument upon the releasing pins while exerting a slight turning pressure upon the plug, and it is one aim of the present invention to provide the plug with a safety plate which prevents turning of the plug sufficiently 15 to operate the lock, even though the locking pins may be picked from their initial plug-locking positions.

There are other ways of releasing locks of the type above mentioned, for instance, by 20 drilling away the front portion of the plug sufficiently to permit introduction of a thin metal strip between plug and cylinder for holding the locking pins released after they have been picked to released position; by 25 drilling the plug or cylinder and portions of the locking pins; and by applying a wrench or the like to the outer end of the cylinder, 30 forcibly turning the latter and thereby shearing its safety locking means, and finally removing the cylinder and plug bodily. It is a further object of the invention to make adequate provision whereby the lock cannot be 35 released by any of these methods.

With the foregoing in view, the invention resides in the novel subject matter hereinafter described and claimed, description being accomplished by reference to the accompanying 40 drawing.

Fig. 1 is a top plan view partly in horizontal section.

Fig. 2 is an outer end or front elevation.

Fig. 3 is a longitudinal sectional view on line 3—3 of Fig. 2.

Fig. 4 is a vertical transverse sectional view on line 4—4 of Fig. 3.

Fig. 5 is a view similar to Fig. 4 but illustrating the only partially released position to 50 which the locking pins may be picked.

In the drawing above briefly described, the preferred details of construction have been disclosed and while these details will be herein specifically explained, it is to be understood that within the scope of the invention as claimed, variations may be made.

The numeral 6 denotes the stationary lock cylinder for passage through a door 7, the inner end of said cylinder being threaded as at 8 for engagement with a housing 9 of a lock structure of conventional form and constituting no part of the present invention. The cylinder 6 is formed with a longitudinal plug bore 10 and with a plurality of transverse pin bores 11. Rotatable in the bore 10 is a plug 12 having the usual lock throw-bar 13 at its inner end and provided at its outer or front end with an outstanding rib or flange 14 disposed at the front end of the cylinder 6. This plug 12 is formed with a longitudinal key-way 15 and with a plurality of pin bores 16 for alignment with the pin bores 11. Spring-pressed locking pins 17 are slidably received in the pin bores 11 and are projectible into the bores 16 of the plug 12 to lock the latter, and 60 releasing pins 18 are slideable in the bores 16 to be actuated by a key 19 for the purpose of moving the locking pins 17 to released position at which their inner ends are flush with the wall of the bore 10.

All of the details above described are common in pin tumbler locks and I will now proceed to describe my improvements.

A safety plate 20 is disposed at the periphery of the plug 12 and is formed with openings 21 through which the locking pins 17 normally pass to enter the pin bores 16. The plug 12 is formed with a longitudinal recess 22 which receives the plate 20 and is of the same length as the latter, said recess however being of greater width in degrees than said plate.

If an attempt be made to pick the lock in the usual way by successively forcing the releasing pins 18 to release the locking pins 17 while exerting a light turning force upon the plug 12, said locking pins 17 may be moved out of the pin bores 16 and when they clear the outer ends of these bores, the thief picking the lock naturally thinks they have 95 100

cleared the periphery of the plug 12. When the last pin 17 has been moved apparently to released position, however, and the plug 12 is turned, it can turn only until one longitudinal side wall of the recess 22 strikes the plate 20, because of the fact that the inner ends of the locking pins 17 still remain in the openings 21 of said plate (see Fig. 5).

Attention is further invited to the fact that 10 the openings 21 are of larger diameter than the pins 18. Thus these pins 18 cannot establish a rigid driving connection between the plug 12 and the loosely mounted plate 22, and consequently turning force applied 15 to said plug 12 when attempting to pick the lock, cannot cause said plate to hold the pins 17 released. When using any known way of picking, the pins would be picked to the position of Fig. 5 but the plug 12 could not rotate 20 sufficiently to open the lock as above explained. If any of the pins should by any possibility be picked to the shear line and supported at picked position by resting upon plate 22, attempt to similarly pick the next 25 pin, would move said plate 22 and allow the previously picked pin to fall back to locking position, for said plate 22 is inaccessible and could not be held against movement.

Inset in the front end of the cylinder 12 30 and projecting laterally from the bore-engaging face thereof into the flange 14, is a case-hardened metal plate 23 which is disposed in front of the pins 16-17. This plate 35 prevents drilling away or otherwise removing a sufficient front portion of the plug 12 to permit introduction of a thin metal strip between said plug and the cylinder 6 for the purpose of holding the pins 17 released after 40 picking them to released position. Hence, anyone attempting to pick the lock in this manner would also be thwarted.

If anyone should succeed in so injuring the 45 plate 23 as to permit drilling the plug 12 or cylinder 6, or should the plug be so drilled 50 away as to remove said plate, even then cutting of the locking pins 17 by drilling is prevented, for the reason that the foremost pin 17 is case-hardened. Hence, this pin cannot 55 be cut by drilling and it consequently guards all of the pins behind it.

Swiveled around the front end of the cylinder 6 is a hard metal ring 24 which so shields 60 said cylinder end as to prevent application of a wrench or the like thereto, so that it can- 65 not be forcibly disengaged from the lock housing 9.

From the foregoing, taken in connection 65 with the accompanying drawing, it will be seen that I have made unique provision for 70 insuring against the usual methods employed for the unauthorized opening of locks, and while the details disclosed are preferably followed as above set forth, variations may be 75 made within the scope of the invention as 80 claimed.

I claim:—

1. An improvement in a lock of the type embodying a cylinder having a longitudinal plug bore and a transverse pin bore, a plug rotatable in said plug bore and having a longitudinal key-way and a transverse pin bore, a 70 spring-pressed locking pin in the pin bore of the cylinder projectable into the pin bore of the plug, and a key-actuated releasing pin in said pin bore of said plug; said improvement 75 consisting of a plate at the periphery of said plug having an opening through which said locking pin normally passes, said plug being formed with a peripheral recess receiving said plate and of greater width in 80 degrees than said plate, permitting limited turning of the plug with respect to the plate if the locking pin be picked out of the pin bore of said plug.

2. A structure as specified in claim 1; together with a transverse hardened metal plate 85 inset in the lock plug and projecting laterally beyond the bore-engaging face thereof at the front end of the cylinder, said hard metal plate being in front of said pins and preventing sufficient drilling of the plug to permit introduction of a thin pin-holding strip between cylinder and plug; and a hard metal ring swiveled on the front end of said cylinder to prevent application of a wrench 90 thereto.

3. A structure as specified in claim 1; together with a transverse hardened metal plate 95 inset in the lock plug and projecting laterally beyond the bore-engaging face thereof at the front end of the cylinder, said hard metal plate being in front of said pin and preventing sufficient drilling of the plug to permit introduction of a thin pin-holding strip between cylinder and plug; and a hard metal 100 ring swiveled on the front end of said cylinder to prevent application of a wrench thereto, said locking pin being hardened to prevent cutting thereof with a drill should 105 said hard metal plate be injured or removed.

In testimony whereof I have hereunto affixed my signature.

WALTER D. HAINLINE.
